UNITED STATES PATENT OFFICE.

ATHERTON D. CONVERSE, OF WINCHENDON, MASSACHUSETTS.

BUILDING-BLOCK.

1,182,980.

Specification of Letters Patent.

Patented May 16, 1916.

Application filed January 17, 1916. Serial No. 73,062.

To all whom it may concern:

Be it known that I, ATHERTON D. CONVERSE, a citizen of the United States of America, and a resident of Winchendon, in 5 the county of Worcester and State of Massachusetts, have invented certain new and useful Improvements in Building-Blocks, of which the following is a specification.

This invention relates to toy building 10 blocks and has for its object the provision of means for locking the various blocks together.

The invention consists in providing the 15 various blocks with one or more grooves in one or more of its faces and providing another face with a projecting tongue having resilient side flanges adapted to grip the side walls of said grooves when inserted therein.

The invention further consists in certain 20 novel features of construction and arrangement of parts which will be fully understood by reference to the description of the drawings and to the claims hereinafter given.

25 Of the drawings: Figure 1 represents a perspective view of a plurality of blocks embodying the present invention locked together in the form of a building. Fig. 2 represents a perspective view of a block 30 showing its grooved face. Fig. 3 shows a perspective view of the same block showing the tongues secured to its opposite face. Fig. 4 represents an end view of said block, and Fig. 5 represents a sectional detail of 35 said block and showing the clamping member in section.

Similar characters designate like parts throughout the several figures of the drawings.

40 In the drawings, 10 is a toy building block having in one face thereof a longitudinal groove 11 and two transverse grooves 12. The side walls 13 of said grooves 11 and 12 are equidistant apart and parallel. To the 45 opposite face 14 of the block 10 are secured the clamping members 15 by means of the headed nails 16. Each clamping member consists of a top plate 17 having formed integral therewith the end portions or 50 flanges 18 the ends of which are held by the nails 16 against the face 14 of the block 10. Preferably the end portions 18 are perpendicular to the top plate 17. The top plate 17 is also provided with two resilient inclined side portions or flanges 19 extending 55 inwardly toward the side face 14, the said

flanges preferably being formed integral with the top plate 17 and flaring from each other, the free ends normally being separated a greater distance than the width of a 60 groove 11 or 12. When the tongue or clamping member 15 is inserted in a groove 11 or 12 of another block, the flanges 19 will be forced toward each other and the resiliency of said flanges 19 will cause the outer 65 faces thereof to grip against the side walls 13 of said groove and lock the two blocks together, preventing their accidental separation. The side flanges 19 are shorter than the end flanges 18 and are free from contact with the face of the block to which the clamping member 15 is secured. When the blocks are locked together the friction between the flanges 19 and the side walls 13 70 will be sufficient to prevent the accidental 75 endwise movement of one block relatively to the other.

While in Figs. 2, 3, 4, and 5 only one form of block is shown, it is obvious that the blocks may be of various shapes and 80 have grooves 11 and 12 variously positioned in one or more of the faces thereof.

The clamping member 15 is readily inserted in a groove 11 or 12 and when once inserted it readily retains the two blocks together until such time as the separation thereof is desired, when such separation may be effected without difficulty. This clamping member 15 is formed from a single piece of sheet metal and is readily struck 85 up into the proper form for use with little difficulty, making it very inexpensive to construct. While the member 15 is little liable to get out of commission, it is obvious that in case this should occur it may be readily 90 replaced by another, which could not be done in the case of blocks having the tongue formed integral therewith.

It is believed that the many advantages 95 of this invention will be fully understood 100 from the foregoing description.

Having thus described my invention, I claim:

1. In a device of the class described, a clamping member consisting of a plate 105 adapted to be secured to a toy building block and having end portions contacting with said block and inclined resilient side portions free from contact with said block, said side portions being adapted to grip 110 upon the walls of a groove in another block when inserted therein.

2. In a device of the class described, a clamping member consisting of a plate adapted to be secured to a toy building block and having end portions contacting 5 with said block and inclined resilient side portions formed integral with said plate and free from contact with said block, said side portions being adapted to grip upon the walls of a groove in another block when inserted therein.
3. In a device of the class described, a clamping member consisting of a plate having at its opposite ends flanges perpendicular to said plate and adapted to be held in 15 contact with a toy building block, said plate being also provided with side flanges flaring
- outwardly from said plate and adapted to grip upon the walls of a groove in another block when inserted therein.
4. In a device of the class described, a 20 clamping member consisting of a top plate adapted to be secured to a toy building block and having formed integral therewith end flanges perpendicular thereto and shorter side flanges flaring outwardly from said 25 top plate and adapted to grip upon the walls of a groove in another block when inserted therein.

Signed by me at Winchendon, Mass., this 5th day of January, 1916.

ATHERTON D. CONVERSE.
